UNITED STATES PATENT OFFICE

141,183

DESIGN FOR A LIGHTER CASE OR SIMILAR ARTICLE

Jacob S. Sherman, Chicago, Ill., assignor to Park Sherman Co., Inc., Chicago, Ill., a corporation of Illinois

Application January 29, 1945, Serial No. 117,662

Term of patent 14 years

(Cl. D48—27)

To all whom it may concern:

Be it known that I, Jacob S. Sherman, a citizen of the United States, residing at Chicago, in the county of Cook and State of Illinois, have invented a new, original, and ornamental Design for Lighter Case or Similar Article, of which the following is a specification, reference being had to the accompanying drawing, forming a part thereof.

In the drawing:

Figure 1 is a perspective view of the back of a lighter case or similar article showing my new design.

I claim:

The ornamental design for a lighter case or similar article, substantially as shown.

JACOB S. SHERMAN.
